UNITED STATES PATENT OFFICE.

HERBERT S. JEWELL, OF MILWAUKEE, WISCONSIN.

METHOD OF SEALING PACKAGES.

1,126,022.

Specification of Letters Patent. Patented Jan. 26, 1915.

Application filed December 29, 1913. Serial No. 809,206.

To all whom it may concern:

Be it known that I, HERBERT S. JEWELL, a citizen of the United States, residing at Milwaukee, in the county of Milwaukee and 5 State of Wisconsin, have invented a new and useful Improvement in Methods of Sealing Packages, of which the following is a specification.

This invention relates to the sealing of 10 containers, cases or packages which are made of heavy flexible material, for instance, fiber board, and which comprise usually a collapsible four-sided body having the longitudinal edges of the blank secured together by staples or similar fastenings, and having at each end four flaps which are secured together, after being closed down, by glue or other adhesive material.

The object of the invention is to provide a 20 simple, expeditious and effective method of closing such containers.

In practising this method in the best and most satisfactory manner the container is set up with the four bottom flaps temporarily closed and is then filled with the packages or other goods to be packed in the same. The upper flaps are then glued and closed upon the contents. A sealing or closing frame is then applied to the upper end 30 of the container, confining this end and the freshly glued flaps thereof. This sealing or closing frame is so constructed that in its normal condition it is sufficiently rigid to confine the four-sided end portion of the 35 container and hold the adjacent four flaps down and in position while manipulating or inverting the container, but is expandible so that it can be readily removed from the container when its presence is no longer required on the same. The container is then inverted, thereby bringing the weight of the 40 contents upon the freshly glued flaps which are now held in position upon a supporting surface by the weight of the contents. The sealing frame is now expanded and removed 45 from the container and the latter is allowed to remain in this condition until the adhesive has set. The flaps at the opposite or upper end of the container are now glued 50 and closed down and the closing frame is applied to this end of the container. The container is next inverted, bringing the weight of the contents upon the freshly glued flaps, the closing frame is expanded 55 and removed and the container is allowed to remain in this position until the adhesive

has set. If desired, however, the flaps at one end of the container may be permanently secured together upon a former or other support before the packages or goods are placed in the container, in which case the closing frame is used only in connection with the upper flaps. The frame is applied to these flaps after they have been glued and closed down upon the contents and the frame remains on the container while the latter is being inverted and is then removed after the container is placed upon a suitable support.

In the accompanying drawings: Figure 1 is a diagrammatic plan view of an apparatus which can be advantageously used in practising this method. Fig. 2 is a perspective view of the blank of the container. Fig. 3 is a perspective view of the container with the flaps at both ends closed and the expandible sealing frame applied to the flaps at the upper end. Fig. 4 is a top plan view and Fig. 5 a bottom plan of the expandible sealing frame. Fig. 6 is a vertical section on line 6—6, Fig. 4. Fig. 7 is a plan view showing the frame opened or expanded. Fig. 8 is a plan view showing a modified construction of the sealing frame. Fig. 9 is a fragmentary plan view, partly in section, of one end of the frame. Fig. 10 is a fragmentary elevation of one end of the frame, on an enlarged scale.

As represented in Figs. 2 and 3, the container comprises a four-sided body 10 having at each end two pairs of flaps 11 and 12 which are designed to be folded down successively, the flaps 12 upon the flaps 11.

Referring to Figs. 4-7, the sealing frame represented in these figures is an open, four-sided frame comprising two like parts A, each comprising a side bar 13 and an end bar 14 arranged at right angles to each other and rigidly secured together. The two parts of the frame are connected at one corner by a hinge 15 and at the diagonally opposite corner by a releasable fastening of any suitable construction. The fastening which is shown in the drawings consists of a latch 16 and a staple 17.

Each end bar 14 is provided at its upper edge with an inwardly projecting plate or lip 18 which bears upon the outermost flaps when the frame is applied to the container, as represented in Fig. 3. The bars of the frame are preferably constructed of wood and a sheet metal facing and are rounded

downwardly on their inner sides, or otherwise made flaring downwardly, to facilitate the application of the frame to the closed container. The holding plates or 5 lips 18 are so thin that they can be readily withdrawn from underneath the container without disturbing the freshly glued flaps.

Referring to Fig. 1, 19 represents a conveyer which carries to the apparatus 10 packages 20 which are to be packed in the containers. 21 represents a table arranged near the delivery end of the conveyer. Each container 22 to be filled is placed upon this table with the lower flaps temporarily 15 closed. The packages or other goods are then placed in the container, the upper flaps are glued and closed down and the expandable sealing frame is applied to the same. 20 23 represents a slowly rotating table which is arranged adjacent to the filling table 21. The filled container with the frame applied to the upper flaps thereof is inverted and placed upon the rotating table. The sealing frame is now removed from the container 25 on the table and applied to the next container which has been filled. The rotary speed of the table 23 is such that the time occupied in making one revolution is sufficient to allow the glue to set, usually about 30 seven minutes. The rotary table is kept full of filled containers and they are removed therefrom, one after another, and placed upon a table 24 where the upper flaps are glued and closed down and a sealing frame is applied to the same. The container, which is now closed at both ends, is then inverted and placed upon a conveyer 35 25 which carries the containers away and is so arranged as to length and speed that the adhesive has time to set before the containers are delivered by this conveyer. In this method of sealing 40 containers the same sealing frame is used on one container after another, the frame remaining on the container only until the latter has been inverted and placed upon the supporting surface where the weight of 45 50 the contents holds the flaps in place until

the adhesive has set. The number of sealing frames which is required for practising the process is therefore very small.

Figs. 8, 9 and 10 represent a sealing frame in which one end bar 26 of the frame 55 is permanently secured to the two side bars 27 and the other end bar 28 is movably connected with the side bars by suitable means, for instance, as shown, by horizontal guide pins 29 secured to the side bars 27 and engaging in openings 30 in the end bar 28. The latter is detachably secured to the side bars by suitable fastenings, for instance, by latches 31 and staples 32.

I claim as my invention:

1. The method of sealing the flaps of a filled container which consists in applying an adhesive to the flaps at one end of the container, closing the flaps, confining the end of the container and its closed flaps 70 against movement out of the closed position, inverting the container and placing the same upon a support while the end of the container and the freshly glued flaps are so confined, releasing the closed end of the 75 container after it has been placed upon said support and allowing the adhesive to set.

2. The method of sealing the flaps at both ends of a container which consists in temporarily closing the flaps at one end thereof, filling the container while resting on these flaps, applying an adhesive to the flaps at the opposite end, closing said glued flaps, confining the end of the container and its glued flaps against movement out of the 85 closed position, inverting the container and placing the same upon a support while the end of the container and the freshly glued flaps are so confined, releasing the closed end of the container after it has been so 90 placed upon said support, allowing the adhesive to set, applying an adhesive to the flaps at the opposite end of the container and sealing said flaps in like manner.

Witness my hand in the presence of two 95 subscribing witnesses.

HERBERT S. JEWELL.
